Des. 203,096

Patented Nov. 30, 1965

203,096

LUGGAGE CASE

Emmett H. Heitler, Denver, Colo., and Robert K. Fujioka,
Los Angeles, and Tim M. Uyeda and Arthur W. Ells-
worth, South San Gabriel, Calif., assignors, by mesne
assignments, to Samsonite Corporation, Denver, Colo.,
a corporation of Colorado

Filed Nov. 5, 1962, Ser. No. 72,389

Term of patent 14 years

(Cl. D87—5)

FIG. 1.

FIG. 2.

FIG. 3.

FIG. 5.

FIG. 6.

FIG. 4.

FIG. 7.

FIG. 8.

FIG. 9.

FIG. 10.

FIG. 11.

FIG. 12.

FIG. 13.

FIG. 1 is a front perspective view of a luggage case embodying our new design, wherein a centrally disposed beam on the top of the case terminates short of each end of the case with a frame which is narrower than the beam extending in alignment with the beam along the remainder of the top of the case and along each end thereof and each of the shells is provided with a groove spaced inwardly from the peripheral edge thereof;

FIG. 2 is a top plan view of the luggage case of FIG. 1;

FIG. 3 is a side elevation of the luggage case of FIG. 1;

FIG. 4 is an end elevation of the luggage case of FIG. 1;

FIG. 5 is a fragmentary section, on an enlarged scale, taken along line 5—5 of FIG. 2;

FIG. 6 is a fragmentary section, on an enlarged scale, taken along line 6—6 of FIG. 2;

FIG. 7 is a front perspective view of an alternative luggage case embodying our new design, which includes the aforesaid beam but in which the shells lack the peripheral grooves and the aforesaid frame is omitted.

FIG. 8 is a top plan view of the luggage case of FIG. 7;

FIG. 9 is a front perspective view of another alternative luggage case embodying our new design, which includes the aforesaid beam but in which the shells have rounded corners and in which the aforesaid frame is omitted;

FIG. 10 is a top plan view of the luggage case of FIG. 9;

FIG. 11 is a front perspective view of another alternative luggage case embodying our new design, in which

a modified form of the aforesaid beam terminates short of each end of the luggage case, with a frame which is narrower than the beam extending in alignment with the beam along the remainder of the top of the case and along each end thereof and in which the corners of the shells are rounded;

FIG. 12 is a top plan view of the luggage case of FIG. 11; and

FIG. 13 is an end elevation, on an enlarged scale, of the luggage case of FIG. 11.

The essential features of our design are shown in full lines.

We claim:

The ornamental design for a luggage case, as shown and described.
